[57] CLAIM

The ornamental design for a one-man outrigger canoe, as shown and described.

DESCRIPTION

FIG. 1 is a top plan view of a one-man outrigger canoe showing our new design;

FIG. 2 is a right side elevational view thereof;

FIG. 3 is a bottom plan view thereof;

FIG. 4 is a left side elevational view thereof;

FIG. 5 is a front elevational view thereof;

FIG. 6 is a rear elevational view thereof;

FIG. 7 is a fragmentary portion of the top plan view thereof on a greatly enlarged scale;

FIG. 8 is a fragmentary portion of the top perspective view thereof on a greatly enlarged scale;

FIG. 9 is a fragmentary portion of the top plan view of a second embodiment of the one-man outrigger canoe;

FIG. 10 is a fragmentary portion of the top perspective view of FIG. 9 on a greatly enlarged scale.
